UNITED STATES PATENT OFFICE

JOHN H. BELL, OF SOUTH ORANGE, NEW JERSEY, ASSIGNOR TO WESTERN ELECTRIC COMPANY, INC., OF NEW YORK, N. Y., A CORPORATION OF NEW YORK

DUPLEX TELEGRAPH SYSTEM

Application filed February 28, 1928. Serial No. 257,574.

This invention relates to duplex telegraph systems and more particularly to systems of this type in which grounded telegraph circuits are operated in conjunction with cable lines.

5 The telegraph traffic between large and distant cities is ordinarily directed over a large number of conductors placed in close proximity to each other in a cable. In order to avoid disturbances from external sources as well as the mutual disturbances between the circuits within the cable, such cable circuits are commonly arranged with a metallic return. Where the distances are great repeater stations are placed at suitable intervals in a 10 well known manner.

In order to utilize such a cable and its associated equipment to the best advantage it is desirable that it should serve points located 20 within certain distances on either side of the path of the cable. Telegraph stations located at a distance from the cable, hereinafter termed "branch stations", would ordinarily be operated as grounded circuits over single 25 open-wire lines. When such circuits have been routed through a section of a cable, it has hitherto been the practice to run the open-wire line to the nearest repeater station and to insert a repeater therefor at this point, so 30 that the open-wire section could be operated on a grounded basis and the cable section on a metallic basis. This has been found necessary since in case an open-wire circuit were connected directly without a repeater to a 35 single conductor in a multi-conductor cable, in accordance with methods hitherto employed, the transmitting effectiveness of the circuit would be reduced as a result of extraneous interference.

40 The present invention provides for a circuit arrangement whereby an open-wire line from a distant branch station may be connected to a cable pair without intervening equipment, and may be cut in at the point 45 where it reaches the cable, without the necessity of running the line as an open-wire line along with the cable to a cable station. The cable pair is so connected, and the repeater or terminal circuit so arranged, that disturbances set up in the pair by other similarly

connected cable pairs are completely neutralized and do not interfere with the reception of signals at the cable station. Since in accordance with the present practice the distance between cable stations is considerable, averaging about 100 miles, substantial savings in line material and labor may result from the adoption of an arrangement such as 55 here proposed.

In accordance with the present invention 60 the cable station, which may be either a repeater station or a terminal station communicating with a branch station, includes a line relay with a plurality of windings arranged 65 symmetrically with respect to the local transmitting circuit. One conductor of the cable pair is directly connected at its far end to the open-wire line, and serves to transmit the signals; the other, or return conductor is 70 grounded at its far end either directly or through an impedance and serves as a neutralizing conductor. The cable pair with its associated open-wire line and impedance is balanced with respect to the transmitting circuit by an artificial line at the cable station, 75 so that signals may be transmitted without affecting the receiving relay at that station. The windings of the line relay are, furthermore, connected to the cable pair in such a manner that disturbances entering these 80 windings are neutralized therein.

An embodiment of the invention is schematically illustrated in the accompanying drawing in which Fig. 1 shows a general arrangement of a cable with its associated repeater and terminal stations and outlying branch stations, and Fig. 2 is a more detailed 85 showing of a branch station, a cable station and the interconnection therebetween.

Referring particularly to Fig. 1 a cable 10, 90 containing a plurality of twisted pairs, of which only a few such as 13, 14, 15 and 16 have been shown, extends between terminal stations A and B and is divided into sections by intermediate repeater stations E and F. 95 Branch stations C and D which may be located at some considerable distance from the line of the cable are connected by means of open-wire lines 11 and 12, respectively, to certain pairs within the cable. Thus line 11 100

is assumed to reach the cable at a point G, and connection made directly to one of the conductors of the pair 15.

The point G may be located a considerable distance from repeater E, in some instances 5 as far as 60 or 80 miles. In accordance with the present practice the open-wire line after reaching the point G would have been continued as an open-wire line parallel to the 10 cable until it reached the nearest repeater E. 15 In accordance with the proposed arrangement this has been obviated and advantage taken of the presence in the cable over that distance of an idle pair of conductors.

The line circuit for station C may be terminated 20 at repeater E or may continue over the pair 16 to terminal station A, as shown.

The open-wire line 12 is similarly connected at point H to the pair 14 which terminates at 25 station B.

The latter circuit is shown more in detail 30 in Fig. 2. Branch station D which is of the grounded duplex type, comprises a double-wound polarized relay 20 the windings of 35 which are connected in the well known differential manner for duplex operation, to line 12 and to artificial line 21, respectively, and have their mid-points connected through transmitting key 22 to sending batteries 23 and 24. Relay 20 by its armature controls a 40 local circuit for the sounder 25.

The cable station B is shown as a terminal 45 station of the differential duplex type comprising a four-winding polarizing relay 30 having an armature for the control of the receiving equipment R, which may be of any 50 desirable type such as a sounder. Transmitting key 31 and its associated sending batteries 32 and 33 are connected in duplex relation to the windings of relay 30. The station B may, however, be a repeater station in 55 which case the receiving equipment R and the key 31, and batteries 32 and 33 would be replaced by the receiving and transmitting 60 equipment of a repeater in a well known manner.

The windings 34 and 35 of relay 30 are 65 each connected to a conductor of the pair 14, which, as shown in Fig. 1, is included in the cable 10 and terminates at point H. At this 70 point the line conductor of the pair 14 which is connected to winding 34, is brought out and connected directly to the open wire line 12 and the return conductor of the pair 14, 75 which is connected to winding 35, is similarly brought out and is connected to ground. The impedance 40 may be included in this ground 80 connection for purposes which will be described hereinafter. An artificial line 38 is 85 connected to windings 36 and 37 of relay 30.

The operation of this system may be described as follows: It will first be assumed 90 that a message is being transmitted from station D to station B. The circuit may then 95 be traced from either of the sending bat-

teries 23 or 24 over key 22. It divides into one branch through one winding of receiving relay 20, artificial line 21 to ground, and another branch through the other winding of relay 20, open-wire line 12, the line conductor 70 of the pair 14, windings 34 and 36 of relay 30, artificial line 38 and winding 37 to ground. Relay 20 remains unoperated in this circuit. The windings of relay 30 are so wound and apportioned that they cooperate 75 to control the armature of relay 30, which thus repeats the received impulse into the receiving circuit R.

Next assuming that a message is being transmitted from station B to station D an 80 impulse produced by the operation of key 31 at station B would take the following paths, from either of the batteries 32 or 33, over key 31, then over two branches, one branch leading over winding 36, artificial 85 line 38 and winding 37 to ground; the other branch leading over winding 34, the line conductor of the pair 14, open-wire line 12, the two windings of relay 20 in series and artificial line 21 to ground. Relay 20 in operating 90 controls the sounder 25. As regards relay 30 in order to prevent the operation thereof, under the conditions just described, the artificial line 38 must be adjusted to counter-balance not only the cable pair 14 but also 95 the open-wire line 12 and its terminal station. The circuit arrangement shown in Fig. 2 thus provides for satisfactory duplex operation.

Since the impulses are transmitted over 100 only one of the conductors of the pair 14 disturbances, due to such impulses, occur in the cable which, however, will not influence the telephone or telegraph circuits which utilize both conductors of their pairs. The conductors of such pairs are interposed by twisting 105 and may be connected to the equipment at the cable stations in such a manner that the disturbances will be neutralized.

The invention is particularly directed to 110 the prevention of disturbances in circuits such as shown in Fig. 2, where only one conductor of a cable pair is used for the transmission of signals. Let it be assumed that another pair 17 serves to interconnect an 115 open-wire line, such as 12, and a cable station, such as B. An impulse transmitted over the line conductor of pair 17 would, on account of its close proximity thereto, induce a disturbing impulse in each of the conductors of pair 14. These disturbing impulses would move in the same direction in the two conductors within the cable and consequently would produce opposite effects in 120 the windings 34 and 35. The impulse in the line conductor traverses windings 34, 36 and 37 which have an accumulative effect upon the armature, whereas the impulse in the return conductor traverses winding 35 only, 125 and in a direction to counteract that trav- 130

ersing the other windings. In order that the opposite effects of the impulses upon relay 30 may be equal and therefore be neutralized it is essential that the amplitudes of the induced impulses and their phase relation be properly governed by the impedances of the two paths. This may be attained by introducing an impedance 40 in the ground connection at point H, which should be substantially equal to the impedance of the open-wire line 12 with associated terminal equipment. However, when the cable pair 14 is very long the effect of the impedance 40 may be negligible in which case this impedance may be eliminated and point H directly grounded.

What is claimed is:

1. In a telegraph system, a single open-wire line, a duplex station for said line, a pair of conductors, additional conductors of other signaling circuits immediately adjacent to said pair, a duplex cable station for said pair, said open-wire line being directly connected to the free end of one conductor of said pair, and means associated with the free end of the other conductor of said pair to balance said open-wire line with respect to said cable station.

2. In a telegraph system, two cable stations, a receiving relay at one of said stations, a cable for interconnection of said stations, an open-wire line, a grounded terminal station for said line, a point of junction on said cable for said line located between said cable stations, a pair of conductors in said cable connected to said relay, a connection to ground and a connection to said line for said pair of conductors at said point of junction.

3. In a telegraph system, an open-wire line, a grounded terminal station for said line, a multi-conductor cable, a cable station for said cable, a receiving relay at said cable station, a first conductor in said cable for direct interconnection of said line and said receiving relay, a second conductor in said cable arranged to form a twisted pair with said first conductor, and connected to said receiving relay, and a ground connection at the free end of said second conductor.

50 In witness whereof, I hereunto subscribe my name this 24th day of February, 1928.

JOHN H. BELL.
